US00D500319S

(12) **United States Design Patent** (10) Patent No.: **US D500,319 S**
(45) Date of Patent: **** Dec. 28, 2004**

(54) **MOBILE USER INTERFACE DEVICE**

(75) Inventor: **Joe Wada, Malmo (SE)**

(73) Assignee: **Sony Ericsson Mobile Communications AB (SE)**

(**) Term: **14 Years**

(21) Appl. No.: **29/199,179**

(22) Filed: **Feb. 11, 2004**

(30) **Foreign Application Priority Data**

Sep. 2, 2003 (EM) 69844

(51) LOC (7) Cl. **14-02**

(52) U.S. Cl. **D14/401**

(57) **CLAIM**

The ornamental design for a mobile user interface device, as shown and described.

DESCRIPTION

FIG. 1 is a top view of a mobile user interface device showing my design;

FIG. 2 is a bottom view thereof;

FIG. 3 is left side view thereof;

FIG. 4 is right side view thereof;

FIG. 5 is rear view thereof;

FIG. 6 is a front view thereof; and,

FIG. 7 is a top perspective view thereof.
